[57] CLAIM

The ornamental design for a terminal for an electrical connector, as shown and described.

DESCRIPTION

FIG. 1 is a perspective view of a terminal for an electrical connector showing an embodiment of our new design;

FIG. 2 is a top plan view thereof;

FIG. 3 is a side elevational view thereof, the opposite side being a mirror image;

FIG. 4 is a bottom plan view thereof;

FIG. 5 is a front elevational view thereof;

FIG. 6 is a rear elevational view thereof; and,

FIG. 7 is a partially cutaway, side elevational view thereof taken along line 7—7 of FIG. 5.

FIG. 1

FIG. 2

FIG. 3

FIG. 4

7
FIG. 5FIG. 6

FIG. 7
